2 Sheets-Sheet 2

UNITED STATES PATENT OFFICE.

RUSSELL H. BOWEN, OF PHILADELPHIA, PENNSYLVANIA, ASSIGNOR TO THE AMERICAN PULLEY COMPANY, OF PHILADELPHIA, PENNSYLVANIA, A CORPORATION OF PENNSYLVANIA.

SHAFT HANGER.

Application filed September 1, 1921. Serial No. 497,780.

To all whom it may concern:

Be it known that I, RUSSELL H. BOWEN, a citizen of the United States, residing in Philadelphia, in the county of Philadelphia and State of Pennsylvania, have invented 5 certain new and useful Improvements in Shaft Hangers, whereof the following is a specification, reference being had to the accompanying drawings.

10 My invention relates to shaft hangers and the like, and is especially concerned with shaft hangers of sheet metal type. Though my invention is to some extent applicable to other hangers, my principal aim, nevertheless, is to secure advantages that are greatly enhanced by sheet metal construction,—such as combined strength, rigidity and lightness; facility, simplicity, quickness, and economy in manufacture; and a generally neat and pleasing appearance. Other advantages that can be secured through my invention include excellent adaptation in strength of the various parts of the hanger to the stresses to which they are subjected 15 in service; stiffness of the hanger, and exemption from working or loosening of its parts in service; and an almost entire freedom from crevices or openings liable to catch and accumulate lint, dirt, oil or grease 20 that would add to the fire hazard in case of a "hot box" at a shaft bearing.

How these and still other advantages may be realized through my invention will appear from my description hereinafter of the 25 best embodiments known to me.

In the drawings, Fig. I is a perspective view of a preferred form of hanger constructed in accordance with my invention.

Fig. II is a side or edge view of the 40 hanger shown in Fig. I, from the left of Figs. I and III.

Fig. III shows a vertical longitudinal section through the hanger at right angles to Fig. II, taken as indicated by the line 45 III—III in Fig. II.

Figs. IV, V, and VI are in the main transverse sectional views, taken as indicated by the correspondingly numbered section lines in Fig. III, illustrating the configuration 50 and construction of the hanger legs and of the cross brace.

Figs. VII and VIII are fragmentary cross sectional views, taken as indicated by the lines VII—VII and VIII—VIII in

Fig. III, illustrating the mounting of some 55 of the bearing-supports of the hanger.

The shaft hanger illustrated in the drawings is of what may be termed the "straddling" type, comprising a pair of principal strength members 2, 2 with an opening 3 60 between them for the shaft and its bearing (not shown) that are to be supported. (See Figs. I—III.) The hanger is shown in the upright position in which shaft hangers are commonly used; and for the sake of 65 convenience and brevity, I have hereinafter (as a rule) described it in terms especially applicable to that position. It will be understood, however, that the hanger may be used in other positions,—in reference to 70 which, of course, some of the terms here employed might seem less appropriate.

As shown, the strength members 2, 2 on either side of the shaft (when in place) are hollow, and are in the form of downward 75 tapering legs or standards with feet 4 at their upper ends for attaching the hanger to a floor or roof beam (not shown), or to any other supporting structures. Between the side legs 2, 2, is a cross-brace member 5 80 having the general form of a transverse vertical web; and also a bottom member or yoke 6, which is readily detachable from the lower ends of the legs to facilitate introduction of the shaft into the shaft opening 3. 85 For supporting the shaft and its bearing in the opening 3 and maintaining proper alignment, the hanger is provided with upper and lower supports 7 and 8 extending vertically through the transverse members 90 5 and 6, as well as with lateral supports 9, 9, extending transversely through the legs 2, 2 at either side of the opening 3. These bearing-supports 7, 8 and 9, 9 have the usual form of set-screws, and are provided 95 with adjusting nuts 10, 11 and 12, 12 mounted on or in the various members 5, 6 and 2, 2 as hereinafter described,—as well as with lock or clamping nuts 13, 14 and 15, 15 bearing against the outer sides of said members 100 through interposed washers 16. As shown, the side legs 2, 2 are only approximately vertical, sloping outward and diverging somewhat from their lower ends toward their upper ends, so as to give the hanger an 105 amply broad transverse "base" at the feet 4.

The legs, 2, 2 are hollow, as already mentioned. For convenience and brevity, they

may be regarded as "facing" toward the shaft (not shown) supported by the hanger, and various portions of their contours or walls (see Figs. I, III, IV to VII) may be 5 correspondingly distinguished as "backs" *a*, "sides" *b*, and "bellies" *c*. (The use of the word "sides" or "flanks" in this "leg anatomy" to designate the leg surfaces to right and left in Fig. II must not be confused, of course, 10 with the use of similar terms, e. g., "side legs" and "sidewise," to express the relation of parts at right and left of Figs. I, III, and IV in reference to the hanger as a whole and to the position of the shaft and bearing supported by it.) Preferably (though 15 not necessarily), the legs 2, 2 are closed—or virtually so—at least from the hanger feet 4 to the lateral bearing-supports 9, 9, and even beyond said supports, between 20 them and the bottom member 6. Preferably, also, each of the legs 2 is formed of a single piece of sheet metal pressed or bent to shape with edges in proximity or abutting along the bellies *c*. As shown, the legs 2, 2 are of 25 round tubular form substantially from end to end. They are not truly circular, however, but more nearly elliptical, with the major axes of the ellipses extending from right to left in Fig. II, so as to give the legs 30 and the hanger ample strength in that direction.

Referring, now, more especially to Figs. I, III, IV and V, it will be seen that the hanger comprises a web plate 20 that extends through the bellies *c* of the legs 2, 2, 35 above the shaft opening 3, into their interiors. An intermediate portion of the plate 20, between the legs 2, 2, is of relative narrow vertical width, and forms the web-like 40 cross-brace 5, which interconnects the legs and serves to strengthen and stiffen the hanger as a whole sidewise (i. e., to right and left in Figs. I and III). Within and adjacent the legs 2, 2, the plate 20 "widens" 45 vertically to form longitudinal internal webs 21, 21 in the legs that extend sufficiently below the transverse member 5 to reinforce and stiffen the legs (sidewise of the hanger, in their common plane) below said 50 member, as well as at their junctions with it. They also brace the legs 2, 2 relative to the member 5, and reinforce and stiffen the hanger as a whole sidewise. In a downward direction, these webs or strength members 21, 21 extend substantially to (i. e. as far as) the lateral bearing supports 9, and then on past them to the lower ends of the legs. This they do in various ways, as will become apparent from further description. 55 Referring especially to Fig. III, it will be seen that the portions of the plate 20 (including its up and down extensions in the legs 2, 2) which constitute the webs 21, 21 60 extend clear to the backs *a* of the legs, and thus resist all inward forces tending to bend

or flatten the legs, or to "rock" them (so to speak) about the ends of the cross-brace 5 or about the feet 4. As shown, moreover, each web 21 is connected or attached to its leg back *a* in the line of meeting, by means of rivet protuberances or tongues 21^x and 21^y on the edges of the plate 20 that project through elongated openings or slots in the backs and are headed over. In the present instance, there are two such connections or 70 attachments: one, 21^x, beside the shaft opening 3, just below the lateral support 9; and the other, 21^y above said opening 3, about on a level with the upper edge of the brace-web 5 at its narrowest. Such attachment greatly fortifies the resistance of web and leg to inward forces such as mentioned above, since it makes the leg back *a* virtually a flange of a T-beam having a web 21 as its web. This same attachment also enables the 80 web 21 to reinforce the resistance of the leg 2 against outward forces tending to bend or rock it, and especially to the side thrust of the lateral bearing-support 9 of the leg in question: for, in the first place, this attachment makes the leg back a flange of a T-beam, as before; in the second place, the mere attachment of leg back to web beside the shaft opening 3 (especially at and adjacent the bearing-support 9) enables this 85 portion of the leg to pull on the web and so add the bending resistance of the web to its own; and in the third place, the attachment of leg back to web above the shaft opening 3 in addition to its just-mentioned 90 attachment lower down makes the intermediate portions of leg and web virtually chords of a sort of "truss." The action in the lower portion of the leg 2 just described is, of course, virtually paralleled in its upper 95 portion, in so far, that is, as the upper portion is affected by outward forces.

Referring, now, especially to Figs. III and IV, it will be observed that the web 21 in each leg 2 is secured and connected or 100 attached to the leg belly *c* adjacent the brace 5, by means of rivets 22 extending through the web outside the leg 2 proper and through external longitudinal belly flanges 23 formed by outward extensions of 105 the sheet metal of the two halves of the belly wall, one such flange at either side of the web. It will be readily appreciated that this belly attachment of the plate 20 coacts with its attachment to the leg back *a* at any 110 and every point to resist very effectually any force tending to rock the leg about the end of the cross-brace 5. Moreover,—disregarding the bottom member 6,—it will be 115 seen that this belly attachment and the attachment 21^x of the leg back *a* to the web 21 above the shaft opening 3 make the portions of the web and of the leg from above the shaft opening downward virtually cantilevers fixed at their upper ends. (The like 120

is true, of course, mutatis mutandis, of the upper portions of leg and web.) As shown, the webs 21, 21 extend from back to belly in the legs 2, 2 for the greater portion of the 5 length of the legs. Also, the belly flanges 23, 23 are shown as extending (with lessening width) downward from the cross-brace 5 to the yoke 6, so that they themselves help to strengthen and stiffen the legs 2, 2 at the 10 sides of the shaft opening. If desired, the attachment of webs to bellies may be supplemented or made stronger by spot-welding or the like. Extending from back to belly in the legs 2, 2 as they do, the webs 15 21, 21 reinforce and stiffen the legs against external crushing, and also against the collapse of back on belly (or vice versa) involved in the bending of a tube. Thus, the legs 2, 2 are reinforced and stiffened by the 20 webs 21, 21 in many ways, especially at and above the sides of the shaft opening 3 and at the upper corners of said openings, where the bending stresses from the side thrust of the lateral bearing-supports 9, 9 on the legs 25 are most severe. The effectiveness in this regard of the downward web extensions 21, 21 of the plate 20 from their connection or attachment to the cross-brace 5 and to the leg bellies *c* above the shaft opening 3 well 30 below the eased and rounded upper corners of this opening deserves especially to be noticed, since they sustain or resist the side thrust cantilever-wise independently (i. e. supplementarily) of the intermediate cantilever strength of the legs 2, 2. The importance of the structural continuity of the webs 21 (regardless of their integral material continuity) in reference to their reinforcing action in various ways will readily 35 40 be apparent.

Referring, now, more especially to Figs. I, III, IV and V, it will be observed that the plate 20 and its web portions 21, 21 are in the present instance arranged centrally 45 with reference to the legs 2, 2, substantially in their common axial or median plane. As shown, also, the web plate 20 with its portions 21, 21 are laminated or multi-ply, being composed of a couple of superposed 50 metal sheets 30, 30. In the portion of each leg 2 where its bearing-support 9 is located, the sheet metal 30 forming the web 21 is locally displaced laterally, by joggling, to accommodate the screw member 9. In this 55 way, the plies 30, 30 are separated for a sufficient vertical distance to form a slot 31 of such length that the screw 9 may occupy any vertical position ever required for proper adjustment of the bearing and 60 shaft in the hanger opening 3,—there being, of course, a corresponding opening in the leg back *a*. In the leg belly *c*, there is a wider and correspondingly elongated opening 32 adapted to admit the support-adjusting nut 12 to seat against the inner or

“belly” edges of the web 21,—this opening 32 being formed by evertting the belly walls *c* (and especially their flange portions 23, 23) to either side sufficiently to admit the nut 12 between the everted portions. With 70 this mounting, the nut 12 is not only concealed and effectually held against turning by the sides 23 of the opening 32, but is allowed to transmit the side thrust of the screw 9 directly to the downward web extension 21 of the plate 20. This thrust the web 21, in turn, transmits to the leg back *a*, and thus distributes to and shares with the leg walls. Also, the web portions 30 at the opening 31 prevent the leg 2 from being 75 flattened or collapsed by clamping between the adjusting nut 12 and the lock nut 15. Referring to Figs. I, III, IV and VII, it will be seen that in the cross-brace web 5 the sheet metal web plies 30, 30 are locally 80 separated at 35, in the way of outward embossing or joggling, to afford a somewhat elongated vertical opening or slot 36 for the accommodation of the upper bearing-support 7 between the plies, and that the adjusted nut 10 is channelled as at 37 so as to be seated and held against turning on the edges of the portion 35. Also it will be seen that the web 5 is itself reinforced and 85 stiffened by opposite outward embossments 90 of its plies, in the form of rounded or circular transverse corrugations 38. These corrugations 38 extend into the interiors of the legs 2, 2, and there terminate a little short of their backs *c*,—the belly flanges 95 23, 23 of each leg being appropriately corrugated at 39 to fit over the corrugations 38. These interfitting corrugations 38 and 39 serve as engagement means for “aligning” the web 5 in proper vertical position 100 105 with reference to the legs 2, 2.

The web plies 30, 30 may be spot-welded to one another over part or all of their area of contact. Also, their attachment to the leg backs *a* may be reinforced or made 110 stronger by electric welding or the like: thus, for example, the rivet projections 21^x and 21^y may be welded in place, or the outer edges of the webs 21 may be welded to the leg backs,—if preferred, even for 115 their entire length.

Referring, now, to Figs. I, II, III, and VIII, it will be observed that the bottom or yoke member 6 is of rounded, approximately circular cross section, is slightly bent or 120 “bowed” downward, and may be formed of a metal tube. At either end, the upper wall is omitted to afford an opening for the leg-end 40, and the side walls are extended upward in the form of rounded and apertured ears or lugs 41, 41. The leg-ends 40 are laterally flattened somewhat as indicated at 42, and are apertured in correspondence with the ears 41 for the reception of bolts 43 that 125 detachably secure the yoke 6 on the leg-ends. 130

The lower vertical bearing-support 8 extends through an elongated opening or slot 44 in the lower wall of the yoke 6, and its adjusting nut 11 has a reduced or narrowed 5 rectangular lower portion 11* that seats in a correspondingly narrow opening 45 in the top wall of the yoke 6, and thus holds the nut against turning.

Recurring, now, to the feet 4, it will be 10 seen from Figs. I, II, III and IV that they are of generally flat rectangular form, but have outstanding tubular sockets 50 in which the legs 2 are received and expanded, as at 51, and also secured by some four rivets 15 52. The feet 4 are reinforced and stiffened with low, flat, hollow central bosses 53, that extend outward from the sockets 50 toward the outer ends of the feet, and have in them elongated bolt-holes 54; also by short hollow, tapering ridges 55 that radiate diagonally (inward and sidewise) from the sockets 50 toward the inner corners of the feet. The feet 4 may be die pressed from sheet metal heavier, preferably, than the rest of the 25 hanger, or may be drop-forged from suitable metal blanks. The upper ends of the legs 2 may be closed by thin cover plates 56 secured (as by spot-welding) over the "bottoms" (upper sides) of the feet 4; they are 30 shown dished to fit into the bosses 53, and apertured in correspondence with the bolt holes 54. These cover plates 56 may conveniently be made by die-pressing thin sheet metal.

35 Having thus described my invention, I claim:

1. A sheet metal hanger comprising a hollow leg, with back, sides, and belly formed of a single piece of bent sheet metal, reinforced and stiffened, sidewise of the hanger, by an internal longitudinal web extending from above the shaft opening of the hanger downward as far as the lateral bearing-support of said leg.

45 2. A sheet metal hanger comprising a hollow leg, with back, sides, and belly formed of a single piece of bent sheet metal, reinforced and stiffened, sidewise of the hanger, by an internal longitudinal web extending 50 from above the shaft opening of the hanger downward beside the same and attached to the back of said leg above said opening and below the lateral bearing-support of said leg.

55 3. A sheet metal hanger comprising a hollow leg, with back, sides, and belly formed of a single piece of bent sheet metal, a transverse member extending laterally from said leg for sustaining a bearing support, and a longitudinal web extending from above the shaft opening of the hanger down in the leg below said transverse member sufficiently to reinforce and stiffen the leg sidewise of the hanger below said member, as 60 well as at its junction therewith.

4. A sheet metal hanger comprising a hollow leg, formed of a single piece of bent sheet metal, a transverse member extending laterally from said leg for sustaining a bearing support, and a longitudinal web extending 70 from above the shaft opening of the hanger down in the leg below said transverse member sufficiently to reinforce and stiffen the leg below said member and having portions riveted into the leg back.

75 5. A sheet metal hanger comprising a hollow leg, with back, sides, and belly formed of a single piece of bent sheet metal, a transverse member extending laterally from said leg for sustaining a bearing support, and a longitudinal web attached to said transverse member extending down in the leg below said transverse member sufficiently to reinforce and stiffen the leg below said member.

80 6. A sheet metal hanger comprising a hollow leg, with back, sides, and belly formed of a single piece of bent sheet metal, and an internal longitudinal web attached to the leg belly above the shaft opening of the hanger extending down beside the shaft opening sufficiently to resist the side thrust of the lateral bearing support of said leg independently of the intermediate strength of the latter.

85 7. A sheet metal hanger comprising a hollow leg, formed of a single piece of bent sheet metal, a transverse member extending laterally from said leg for sustaining a bearing support, and a longitudinal web attached to said transverse member extending down in the leg below said transverse member sufficiently to resist the side thrust of the lateral bearing support of said leg independently of the intermediate strength of the latter.

90 8. A sheet metal hanger comprising a hollow leg, with back, sides, and belly formed of a single piece of bent sheet metal, reinforced and stiffened, sidewise of the hanger, by an internal longitudinal web extending from above the shaft opening of the hanger downward as far as the lateral bearing-support of said leg, and attached to 100 both back and belly of said leg.

105 9. A sheet metal shaft hanger comprising hollow legs, with backs, sides, and bellies formed of a single piece of bent sheet metal, reinforced and stiffened, above and at the sides of the shaft opening of the hanger, by a common interconnecting web plate extending through the bellies of the legs above said opening and having extensions downward into the legs for resisting the side thrust of the lateral bearing-support of the hanger.

110 10. A sheet metal shaft hanger comprising hollow legs, with backs, sides, and bellies formed of a single piece of bent sheet metal, reinforced and stiffened, above and 120

75

80

125

130

at the sides of the shaft opening of the hanger, by a common interconnecting web plate extending through the bellies of the legs above said opening and having extensions downward into the legs attached to the backs thereof at either side of said opening.

11. A sheet metal shaft hanger comprising hollow legs each formed of a single piece of bent sheet metal, with a common interconnecting web plate extending and attached to the backs of the legs above the shaft opening of the hanger and sufficiently below the transverse interconnection formed by the plate to reinforce and stiffen the legs below such connection.

12. A sheet metal shaft hanger comprising hollow legs, with backs, sides, and bellies formed of a single piece of bent sheet metal, and a common interconnecting web plate extending and attached to the backs of the legs above the shaft opening of the hanger and sufficiently below the transverse interconnection formed by the plate to reinforce and stiffen the legs below such connection, and also attached to the bellies of the legs.

13. A metal shaft hanger comprising round, hollow legs, formed of single pieces of metal and closed from the hanger feet to its lateral bearing-supports; and a common interconnecting web plate extending to

the backs of the legs above the shaft opening, and thence downward against said backs to said bearing-supports.

14. A metal shaft hanger comprising round, hollow legs, formed of single pieces of metal and closed from the hanger feet to its lateral bearing supports; and a common interconnecting web plate extending through the leg bellies above the shaft opening of the hanger and having cantilever web extensions down into the legs sufficiently below the transverse interconnections formed by the plate to reinforce the legs against bending collapse below such connection.

15. A metal shaft hanger comprising round, hollow legs, formed of single pieces of metal and closed from the hanger feet to its lateral bearing supports; and a common interconnecting web plate extending through the bellies of the legs above said opening and having extensions downward into the legs for resisting the side thrust of the lateral bearing-supports of the hanger.

In testimony whereof, I have hereunto signed my name at Philadelphia, Pennsylvania, this 30th day of August, 1921.

RUSSELL H. BOWEN.
